UNITED STATES PATENT OFFICE

HERBERT L. CHAPIN, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY

BLACKING MACHINE

Application filed June 15, 1927. Serial No. 199,041.

This invention relates to machines for applying finishing material such as stains, blacking and the like, hereinafter generically termed "blacking", to the peripheral portions of shoe parts such as heels. The illustrated machine is designed for use in blacking the peripheries of the bases of shoe heels having rubber top lifts.

In coating the peripheries of heels attached to shoes, it is possible to apply blacking to the peripheries of heels with great facility when the whole surface of the periphery is to be coated. The problem is more difficult, however, when the heels are provided with rubber top lifts so that the stripe of blacking must be confined between two limits, namely, the rand-crease and the edge of the base-adjacent to the rubber top lift. It is customary also to supply blacking to the inwardly extending marginal surface of the heel in the rand crease and this operation must be accomplished without applying blacking to the shoe upper. This problem was successfully met by the invention set forth in United States Letters Patent No. 1,509,866, granted Sept. 30, 1924 on the application of F. M. Furber. In the machine shown in that patent a rand crease disk was provided for protecting the upper and coating the marginal surface of the heel in the rand crease, and immediately adjacent to this disk there was provided a narrow brush rotatable in the same general direction as the rand crease disk and operating to apply blacking to the side and rear peripheral surfaces of the heel base, blacking means being supplied to the brush by a rotatable member arranged to dip in a blacking receptacle and serving the dual function of supplying blacking to the brush and straightening or combing out the bristles of the brush.

It is an object of this invention to provide an improved organization by the use of which the blacking of shoe parts such as heel bases may be still further facilitated, and which will be constructed and arranged still further to facilitate the removal and replacement of parts and the making of various adjustments.

To this end, in accordance with a feature of

the invention, a pick-up device, illustrated as a rotatable drum dipping in a blacking receptacle, carries a thin film of blacking to a transfer device which supplies blacking to a rotatable brush for applying the blacking to the peripheries of heel bases and which comprises members constructed and arranged also to straighten the bristles of the brush. Preferably readily adjustable scrapers associated with different faces of the drum are provided to control the amount of blacking carried by the drum for delivery to the transfer device. As illustrated, the drum also delivers blacking to a rand crease disk by means of a peripheral flange projecting outwardly from the drum and having associated with it scrapers which control the amount of blacking carried by the peripheral flange for delivery to the rand crease disk.

The illustrated drum, moreover, is provided with an end flange which substantially closes the drum, thereby insuring that the drum will not undesirably churn the blacking in the receptacle and at the same time preventing the accumulation of blacking in the interior of the drum.

To insure that the rand crease disk properly protects the upper of the shoe, the illustrated machine is provided with cleaners contacting with one face of the disk, and to insure that the disk applies sufficient blacking to the surface of the heel base in the rand crease, a plow is provided which co-acts with the applying face of the disk and operates to carry blacking received by the disk outwardly toward its periphery. In accordance with a further feature of the invention, the illustrated rand crease disk is mounted in an adjustable support which also carries the cleaners and the plow, the construction and arrangement being such that the disk with its cleaners and the plow may be simultaneously adjusted to move the disk axially toward or away from the flange of the pick-up drum, thereby insuring that the proper amount of blacking is taken from the drum, without altering the adjustment of the cleaners or the plow with respect to the disk.

In accordance with another feature of the invention blacking is transferred from the

pick-up drum to the brush by a rotary comb comprising a plurality of plate sections arranged helically around the axis of the comb so that they are in staggered relation and provided with projections operating effectively to claw through the brush and straighten its bristles. As illustrated these individual sections are identical and are provided with a plurality of key-ways so that they may be mounted in different angular positions upon the holder to form a helix. Preferably, a support is provided for the rotary comb so arranged that it may be adjusted slightly toward and away from the rotary pick-up drum to control the amount of blacking taken by the comb from the drum for delivery to the brush. As illustrated, the rotary comb is also adjustable toward and away from the axis of the brush to determine the depth to which the teeth of the comb shall dip in said brush bristles. Preferably the driving mechanism for the comb and the brush is such that a hunting action is set up both axially and circumferentially so that any particular portion of the comb contacts with any particular set of bristles only once in about every four hundred revolutions of the brush.

Because of the variation in the heights of heel bases and hence in the width of the stripe of blacking which must be applied, it is found desirable to make the brush in thin sections and to use as many sections as may be necessary for the particular work. Obviously, also, the brush must be removed at intervals for cleaning. Accordingly, still another feature of the invention resides in a brush supporting organization including a quick clamping mechanism to grip the brush upon its holder, in which the holder and a reversible clamping nut are provided with co-acting interrupted threads. This allows the clamping nut to be slipped onto the holder and then brought into tight clamping engagement by a partial rotation. To ensure this result, the ends of the illustrated nut are differently related to its thread so that one end or the other will be sure to clamp the brush tightly. Preferably a projection upon the nut which is used for turning the nut into clamping position is arranged also to serve as a means for driving a rotatable disk which is provided adjacent to one side of the brush to control the spread of the bristles.

These and other features of the invention will now be set forth in detail with reference to the accompanying drawings in which,

Fig. 1 is a side elevation of a machine embodying the invention;

Fig. 2 is a front elevation of the machine with parts broken away and in section;

Fig. 3 is a plan view of the operating parts of the machine with the upper part of the machine cut away;

Fig. 4 is a section on the line IV—IV of

Fig. 3 showing the driving mechanism for the brush and the comb;

Fig. 5 is a plan view of the scrapers cooperating with the cylindrical blacking supply drum;

Fig. 6 is a section on the line VI—VI of Fig. 5 showing the relation of one scraper to the lateral flange of the drum;

Fig. 7 is an axial section through the rotary comb and its eccentric bearing;

Fig. 8 is a detailed view of one of the plates used in making up the comb.

The illustrated machine, which is of the type shown in United States Letters Patent No. 1,509,866 above referred to, is adapted to apply blacking to the sides and rear of the leather heel base 10 of a shoe 12 by means of a rotary brush 14. Blacking is also applied to the top edge of the heel adjacent to the rand crease by means of a rand crease disk 16 (Fig. 3). The brush 14 and the disk 16 are rotatable about angularly related axes as shown in Fig. 3 so that the portions of the disk and the brush which are opposite to the points of application of the work are separated from one another to allow blacking to be supplied individually to the brush and to the disk without interference. Blacking is supplied to the disk 16 by a projecting flange 18 upon a cylindrical drum 20 which dips in a receptacle 22, partially filled with liquid blacking, the projecting flange 18 of the drum 20 having a beveled lateral face 60 which is arranged to pass near and overlap the opposed face of the rand crease disk 16 to transfer blacking thereto. Blacking is transferred from the cylindrical surface of the drum 20 to the brush 14 by a combined blacking pick-up and bristle-straightening comb 24 (Fig. 4) which is rotated in a direction opposite to that of the brush and at a different speed.

As in the machine disclosed in the Letters Patent referred to, the blacking receptacle 22 is supported within a hollow frame 30 by means of a removable pin 32 having an enlarged central portion 34. The blacking receptacle 22 is provided with an extension 36 (Figs. 2 and 3) provided with an opening for engagement with a dowel 38 secured in said frame by a set screw 40 (Fig. 1). The receptacle 22 is also extended forward at 37 to provide for the reception of an adjustable heel rest 42.

In the machine illustrated herein, the blacking is picked up from the receptacle by means of a cylindrical drum 20 which is secured on a transverse shaft 44 (Fig. 3) provided with a gear 46 (Fig. 1) having driving engagement with a worm 48 on a drive shaft 50 journaled in the frame 30 and extending from front to back. This drive shaft 50 is provided with a tight pulley 52 and a loose pulley 54, while the shifting of a belt from

one to the other is accomplished by a belt shifter 56 having an operator's handle 58.

At the right side of the drum 20 a flange 62 (Fig. 3) is provided which practically 5 closes this side of the drum, it being left open at 64, however, to facilitate casting the part and the removal of the core. This flange 62 is of such dimension that it prevents the admission of blacking to the interior of the 10 drum where its accumulation and oxidation might build up a mass of dried blacking, in the course of time, to an extent which would interfere with the proper operation of the machine. The flange 62 minimizes the 15 tendency of the rotation of the drum to churn up the blacking in the receptacle 22 and fill it with bubbles which would render the blacking ineffective in coating the work.

As this drum 20 with its projecting flange 20 18 rotates and dips in the receptacle 22 it picks up a quantity of blacking which is not definitely determined and which varies somewhat with the depth of the blacking in the receptacle. It is desirable, therefore, to control 25 the quantity of blacking on certain surfaces of the drum prior to its transfer to the applying devices. It is also desirable to scrape completely clean other surfaces of the drum in order to prevent the accumulation of 30 dried blacking thereon which would otherwise result. Accordingly, scrapers are provided which are best shown in Figs. 3, 4 and 5, certain of which are directed to the control of blacking upon the beveled circular face 35 60 of the drum and the flange 18. Since the transfer of blacking from this flange to the rand crease disk 16 results from the slight overlapping relation of the two members, it is only necessary for the proper delivery of 40 blacking to said disk that there shall be an annular stripe of blacking around the outer margin of the beveled surface 60. Thus there is provided a stripping scraper 70 having a broad face for engagement with a wide extent 45 of the beveled surface 60 completely to clean surplus blacking from an annular area within the margin of this surface and to prevent its drying and building up. This scraper is mounted on an arm 72 held by 50 means of a set screw 74 (Fig. 5) on a sleeve 76 which passes through an opening in the frame 30 and is held in position therein by a set screw 78. This sleeve furnishes the bearing for a plunger 80 on the right end of which 55 is mounted a controlling edge scraper 82 by means of which it is possible to control the amount of blacking picked up by the outer annular margin of the surface 60 for delivery to the rand crease disk 16. The plunger 80 60 is normally pressed toward the surface 60 of the drum by means of a spring 81 interposed between a collar 84 on the sleeve 76 and a pin 86 passing through a slot in said sleeve into the plunger 80. The outer end of the 65 plunger 80 is threaded for engagement in

a nurled nut 88 by means of which the operator can adjust to a nicety the position of the scraper 82 with respect to the surface 60. When the operator wishes to adjust the scraper 82, he first loosens the nut 88 to allow the spring 81 to push the scraper 82 into engagement with the surface 60 of the flange 18 of the drum and then tightens the nut to draw back the scraper 82 just the desired amount to permit the transfer of the proper supply of blacking to the rand crease disk 16. To prevent the formation of a ring of dried blacking upon the beveled surface 60 of the drum between the surfaces treated by the scrapers 70 and 82 the adjacent edges 20 of the scrapers 70 and 82 are beveled at 90 so that they overlap (as shown in dotted lines in Fig. 4).

Other scrapers are provided for controlling the blacking upon the cylindrical surface of the drum 20 and the right hand surface of the projecting flange 18 and upon the outer surface of the closing flange 62. In the case of the right hand surface of the flange 18 and the outer surface of the closing flange 62, which are parallel but laterally displaced from one another, it is only essential that all the blacking shall be removed in order to keep them clean. In case of the cylindrical surface of the drum, however, it is desired accurately to control the quantity of blacking which is picked up for transfer to the applying brush 14. There is provided, accordingly, a scraper assembly including a block 92 which has an end face for engagement with the right hand surface of the flange 18 (Fig. 5) and this scraper 92 is also provided with a flattened pin 96 which is tiltably mounted in the scraper about an axis situated along side the flattened face of the pin. This pin 96 is provided with a slotted head 98 so that it may be tilted to bring its sharpened corner 100 (Fig. 6) into the desired relation to the outer surface of the flange 62. It will then be clamped in position by means of a bolt 102. This scraper 92 is mounted on a rod 104 passing through a block 106 which is integral with the dowel pin 38 (Fig. 1) which, it will be recalled, serves to assist in the location of the blacking receptacle 22. The clamp bolt 102 also serves to hold the scraper 92 on the rod 104. It will be noted from Fig. 1 that the block 106 is ribbed on its upper surface for engagement with a corresponding groove in the frame 30 so that when the dowel pin inserted in the frame and clamped by the set screw 40, it will be properly positioned approximately to locate the scraper 92 with respect to the drum. This block 106 and the scraper assembly just described may be removed and replaced without disturbing the adjustments effected, simply by detaching the spring 112 and loosening the set screw 40. A spring 108 surrounds the rod 104 and urges the 110 115 120 125 130

scraper to the left, it being possible accurately to adjust this position by means of an abutment screw 110 threaded in a block 111 on the end of the rod 104, this screw rubbing on the end face of the block 106.

The scraper structure 92 is also provided with a blade 94 (Fig. 4) which may be brought into the desired relation to the cylindrical surface of the drum to control the blacking carried along on said surface for transfer to the applying brush 14. A spring 112 (Fig. 1) between an arm of the block 111 and the screw 40 tends to rotate the rod 104 counter-clockwise, as viewed in Fig. 1, to bring the scraper blade 94 into the desired relation to the drum and the position of this blade with respect to the drum may be adjusted by means of hand screw 114 threaded in another arm of the block 111 and engaging the projecting portion of the set screw 40. It should be noted that operation of the hand screw 114 to control the scraper blade 94 does not affect the effective relation to the drum of the end surface of the scraper 92 and the scraper 96. The adjustment of the scraper pin 96 after the machine has been initially set up is only necessary in case of uneven wear between the end of the scraper 92 and said scraper pin 96. It then will be possible to compensate for this by turning the flattened pin 96 in the scraper 92.

As has been brought out already, the application of blacking to the upper edge of the heel adjacent to the rand crease is effected by the concave rand crease disk 16 having an outwardly turned peripheral flange 120 (Fig. 2) as is common in this type of machine. This flange 120 contacts with or rotates closely adjacent to the flange 18 on the blacking supply drum 20 and receives blacking therefrom which is transferred to the work. The disk 16 is clamped upon a shaft 122 by means of a nut 124 which has an integral hub portion in the form of a disk provided with radial slots 126 for a purpose to be later explained. The shaft 122 is journaled in bushings 128 supported in a doubly bifurcated adjustable frame 130. This bifurcated frame 130 is provided with upwardly extending forked portions 132 and similar downwardly extending portions 134 and these forked portions surround outwardly extending arms 136 and 138 (Figs. 2, 3 and 4) which are integral with the frame 30 of the machine. In order to adjust the position of the rand crease disk 16 with respect to the flange 18 of the blacking supply drum 20 so as to control the amount of blacking transferred from one to the other, the bifurcated frame 130 is adjusted laterally by means of screw 140 (Fig. 2) threaded in the lower arm 138 of the main frame and cut to fit closely between the lower arms 134 of the bifurcated frame. The position of the shaft 122 with respect to the frame is maintained by

means of a collar 142 and after the operator has loosened a set screw 144 which passes through the frame arm 138 to engage a part movable with the bifurcated frame, the operator may insert a screw driver through an opening 146 in the arm 134 which is smaller than the head of the screw 140 and by turning this screw, adjust the frame 130 laterally.

It is necessary to keep the convex side of the disk 16 clean in order to prevent smooching the uppers of shoes, the heels of which are being blacked, and to this end cleaners 150 and 152 (Fig. 2) are mounted in a bracket 154 surrounding the enlarged end portion of the shaft 122. The bracket 154 is resiliently pressed toward the rand crease disk by springs within a pair of rods 156 each of which is held in the adjustable bifurcated frame 130 by means of set screws 158. In the upper arms 132 of the adjustable frame 130, there is also mounted a rod 160 supporting a plow 162 which reaches over the upper edge of the disk 16 and is provided with an inwardly directed flange 164 (Fig. 4) for engagement with the face of the disk. In some instances, if the blacking is very thin, there may be a tendency for the blacking to run away from the edge of the disk at the top where the latter carries the blacking over the highest point toward the front of the machine. Hence this flange 164 is so positioned with respect to the circumference of the disk that it tends to drag the blacking outwardly toward the periphery of the disk to increase the supply of blacking and form a bead of blacking at the outer edge of the disk where it is most needed. The position of the rod 160 supporting the plow 162 with respect to the disk 16 may be adjustably determined by means of a clamp screw 166 (Fig. 2). It should now be noted that, having once adjusted the position of the cleaners 150 and 152 and the plow 162 with respect to the disk, it is possible to adjust the frame 130 carrying these members and the rand crease disk to vary the position of the disk with respect to the supply drum 20 without disturbing the adjustment of the cleaners and the plow with respect to the disk.

The rand crease disk 16 is driven from the shaft 44 by a train of gears 270, and the last gear of this train meshes with elongated teeth 272 (Fig. 2) in the shaft 122. Thus the axial adjustment of the rand crease disk shaft 122 does not interfere with its driving connection to the gears 270.

The application of blacking to the base 10 of the heel between the rand crease and the rubber top lift is effected, as previously pointed out, by means of a brush 14 which is mounted for rotation about an axis angularly related to the shaft 122 supporting the rand crease disk. The divergence between

the two axes of rotation is in a substantially horizontal plane so as to separate the disk 16 and the brush 14 at a point diametrically opposite the point where the work is applied 5 to allow the coaction therewith of separate means for supplying blacking to the two applying devices. In order to support the brush 14 for rotation, a headed stud 170 (Fig. 2) is mounted in a depending portion of an 10 adjustable bracket 172 (Fig. 1) and is held therein by means of a wing screw 174. This bracket 172 is clamped upon the main frame 30 of the machine by means of hand wheel 176 threaded on a stud 178 (Fig. 2) 15 which is in turn threaded into the frame of the machine. A slot is provided in the upper end of the bracket so that it may be readily engaged with and disengaged from the stud 178 and the bracket is provided with 20 an inwardly extending rib 180 (Figs. 2 and 3) for engagement in a corresponding horizontal groove in the frame 30 so that the bracket may be removed and readily reengaged in the same angular relation to the 25 frame. The brush 14, itself, is supported upon a sleeve 182 constituting a hub-like extension from a wide flange 184 at its left end. The sleeve 182 is slipped over the stud 170, and the flange 184 is placed in engagement 30 with the head of the stud the sleeve 182 being held rotatably in position on the stud 170 by a collar 186. The flange 184 serves to control the deflection of the bristles at the left side of the brush and is provided with 35 a pin 188 which is entered in one of the slots 126 in the disk portion of the nut 124 used for clamping the rand crease disk on its shaft. This forms a universal driving connection 40 between the disk shaft and the brush regardless of the axial relation of the two members or of the adjustment from front to rear of the bracket supporting the brush. Preferably the brush is made up in thin sections 190 having metal hubs grooved on their 45 inner peripheries to provide for wiring the tufts of bristles. These brush sections 190 are placed upon the sleeve 182, the number of sections being determined by the height of the heel base 10 to be treated, and are 50 clamped thereon by means of a nut 194 (Figs. 2 and 4) having an outward projection 196 by means of which it may be turned.

In order to facilitate the easy application 55 of brushes to the supporting sleeve 186 and their removal therefrom, the sleeve 182 is provided with an interrupted thread (Fig. 4) similar to that used in the breech block of a gun, and the nut 194 is provided with coacting interrupted threads so that the nut may 60 be slid over the sleeve 182 into loose engagement with the hubs of the brush sections and then given a partial rotation by means of the projection 196 tightly to clamp said brush sections upon the sleeve. The design 65 of the nut 194 is such that its opposite ends are

differently located with respect to the threads of said nut. Thus in case a partial revolution of the nut when it is applied to the sleeve 182 does not clamp the brush sections tightly by means of the interrupted threads, then 70 the nut may be reversed with the assurance that the other end can be tightly engaged with the brush.

As in the machine disclosed in the Letters Patent referred to, the deflection of the 75 bristles at the right side of the brush is controlled by means of a concave disk 200 adjustably supported so that it may be brought up against the brush to adjust its width so that the stripe of blacking applied to the heel will completely coat the base 10 without overlapping the top lift 11. In the illustrated machine, the disk 200 is provided with a hub portion 201 reduced to form another hub portion 202 by means of which it is rotatably supported within the hollow end 204 of an arm 206 mounted on a stud 208. The arm 206 may be moved along the stud 208 and held in the desired position thereon by means of a clamp screw 210 which engages with a 80 flattened portion of said stud. In addition the stud 208 may be adjusted from front to back in the machine, so as to bring the outer edge of the controlling disk 200 nearer to or farther away from the ends of the bristles, 85 by moving it along a slot indicated at 212 (Fig. 1) which is in the bracket 172 and clamping it in adjusted position therein. Cleaners 214 and 216 are supported upon the 90 arm 206 to wipe the outer side of the controlling disk 200 and prevent the accumulation of blacking thereon. The projection 196 upon the nut 194 engages a slot 197 in the hub portion 201 and provides a universal 95 driving connection between the brush and the disk 200 irrespective of whether or not the brush and disk are concentric.

The transfer of blacking from the pick-up 100 drum 20 to the applying brush 14 is effected by the rotary comb 24 which is built up on a hub member or holder 220 attached to a stub shaft 222 (Fig. 7) by means of a left-hand thread 224 so that said hub may be screwed up tightly against an enlargement or shoulder 226 on said shaft and held in 105 position thereon without displacement due to the engagement of the comb with the brush. The stub shaft 222 is journaled in an eccentric bushing 228 and is held therein by means of a combined collar and pinion 230 which is pinned to the shaft. The rotary comb 24 comprises a series of plate sections 232, each of which has a hub portion 243 provided with a plurality of key-ways 236. The plates 232 are also provided with outwardly extending lobed portions 238 which have circular faces 240 concentric with the center of the hub portion 234, said circular faces being joined to the hub portions by straight sides, one of 110 115 120 125 130

which forms sharp corners 242 with the circular edges 240. The hub 220 is provided with a key 244 and the rotary comb 24 is assembled by placing successive plates 232 in staggered relation on the hub 220 so that identical points on the plates are helically arranged around the hub, thus rendering the combing action more effective because the point of contact of successive plates is carried across the brush. This is accomplished by mounting each plate on the hub so that the key-way which co-operates with the key 244 is the next succeeding one to the key-way which was associated with said key in the case of the preceding plate. The plates are then clamped on the holder hub 220 by threaded collars 245 and the position of the comb as a whole may be adjusted axially parallel to the axis of the brush by adjusting these clamping collars 245. In the illustrated construction, each of the plates 232 is provided with three key-ways so that the assembled comb as shown in end view in Fig. 4 has three lobed projections, the circular portions 240 of which are arranged to pass over the cylindrical portion of the drum 20 in close relation thereto. Identical points on the plates such as the sharp corners 242 form a helix and are arranged to cut or claw through the bristles of the brush 14 to straighten out said bristles and to prevent their matting. It will be noted that the elements of the three rows of plates are staggered with respect to one another so that they travel in different paths through the bristles of the brush. At the same time, the comb transfers blacking from the pick-up drum to the brush bristles.

The eccentric bushing 228 in which the shaft 220 of the comb is supported is itself supported in a sub-casing 250 indicated in dotted lines in Fig. 4 and provided at its right-hand lower end with a removable journal box 252 surrounding the transverse shaft 44. It is possible, therefore, by tilting the casing 250 about the center of the shaft 44 to cause the plates of the comb 24 to dip more or less deeply into the bristles of the brush 14. An adjusting stop screw 254 determines the position of the casing upon the main frame and said casing is held in adjusted position by means of a clamp bolt 256 passing through a slot 258 in said casing and threaded into the frame 30.

Rotation of the comb 24 is effected by a train of gears 260 shown in dotted lines in Fig. 4 and it will be noted that the adjustment of the sub-casing 250 does not disturb the meshing relation of said gears with the driving gear 262 on the shaft 44, nor does it disturb the relation of the circular edges 240 of the transfer comb 24 to the drum 20.

It may be desired to vary the relation of the circular edges 240 of the transfer comb 24 to the cylindrical surface of the drum 20 to

control the quantity of blacking transferred by the comb, and to this end, the eccentric bushing 228 is provided with a slotted lug 264 (Fig. 4 and 7) by means of which said eccentric bushing may be slightly turned to secure the change of a few thousandths of an inch necessary to get the circular edges 240 in just the desired relation to the drum 20. The eccentric bushing 228 is held in adjusted position by a clamp bolt 266 (Fig. 7).
In order to prevent the teeth of the rotary comb 24 from acting repeatedly upon the same portions of the brush so as to wear away the bristles or to mat down the brush instead of combing it up as desired, the arrangement is such that there is a hunting action between the teeth of the rotary comb and the brush to transfer the point of contact of any particular portion of the comb around the surface of the brush. As a result, an individual plate of the comb only comes into engagement with the same set of bristles of the brush once in approximately every four hundred revolutions of the brush. This circumferential hunting action supplements the effect of the helical arrangement of the plates 232 of the comb, as a result of which there is also a hunting action in a direction parallel to the axis of the comb to transfer the point of contact of any particular portion of the comb axially.

It may be that the blacking which is used will be of such a character that it requires constant agitation in order to prevent the pigment in the blacking from settling. I have provided, therefore, an agitator 280 having laterally extending comb-like teeth (Fig. 3) formed integrally with an arm 282 which is pivotally attached at 284 to the blacking receptacle 22. This arm 282 is provided with an overhanging cam flange 286 curved as shown in Figs. 1 and 4 for engagement by a cam roll 288 upon an arm 290 secured to the shaft 44 by a clamp 292. During the operation of the machine, the rotation of the shaft 44 will repeatedly lift the agitator by reason of the engagement of the roll 288 beneath the flange 286 and subsequently allow the agitator to drop back into the receptacle. A buffer 294 (Fig. 4) has been provided at the forward end of the agitator to soften the blow of the agitator against the bottom of the receptacle. It will be noted, therefore, that the arrangement is such that the agitator 280 will be removed with the receptacle so that both may be cleansed whenever it is necessary to clean the receptacle. It is only necessary to stop the machine in such a position that the roll 288 is not in engagement with the flange 286.

Having set the machine in operation, the heel bases of shoe heels may be treated by the applying brush 14 by positioning the heels upon the work support 42 and turning the shoes to bring all parts of the horseshoe-

shaped peripheries of the heel bases into engagement with the applying brush. It will be understood that the top edges of the heels adjacent to the rand crease are coated at the same time by reason of their engagement with the rand crease disk 16. The supply of blacking picked up by the peripheral surface of the cylindrical drum 20 may be controlled by the proper adjustment of the scraper 92 through the screw 114 and a supply of blacking for delivery to the rand crease disk may be similarly controlled by the proper adjustment of the hand screw 88 to determine the position of the scraper 82 with respect to the flange 18 of the drum. The width of the stripe of blacking applied by the brush 14 is controlled by adjusting the controlling disk 200 at the right side of the brush and more or less compressing the bristles of the brush against the abutment flange 184, this adjustment being effected by loosening the hand screw 210 (Fig. 3) so as to slide the bearing supporting said controlling disk 200 along the stud 208.

When it is desired to remove the rotary comb 24 for cleaning, it is only necessary to lift up the protecting cover 276 which is pivoted at 278 (Fig. 4) and to unscrew the hub 220 of the comb from the stub-shaft 222. It may be as easily replaced without affecting any adjustment. When it is desired to remove the brush 14 for cleaning or replacement, the supporting bracket 172 will be removed by loosening the hand wheel 176, after which the sleeve 182 carrying the brush may be removed axially by loosening the thumb nut 174 and taking the shaft 170 out of said bracket. It is possible then to remove the brush sections very quickly by giving a partial turn to the nut 194 by pressure on the projection 196, after which the end of the brush sections may be slipped off over the collar 186 and the end of the stud 170. Removal of the pin 32 permits the removal of both the blacking receptacle 22 and the agitator 280 as the said receptacle with its extension 36 is lowered out of engagement with the dowel 38.

Having thus described my invention, what I claim as new and desire to secure by Letters Patent of the United States is:

1. In a blacking machine, an applying brush, a blacking receptacle, pick-up means for lifting blacking from the receptacle, and means for transferring the blacking from the pick-up means to the applying brush comprising members constructed and arranged to operate also to straighten the bristles of the brush.

2. In a blacking machine, an applying brush, a blacking receptacle, a rotary cylinder for taking blacking from the receptacle, and a comb for transferring blacking from the cylinder to the applying brush comprising members constructed and arranged to ex-

ert a clawing action on the bristles of the brush to straighten the bristles.

3. In a blacking machine, a brush for applying blacking to heel peripheral surfaces, a blacking receptacle, a pick-up device for taking blacking from the receptacle, and a comb comprising a holder and a plurality of lobed sections arranged in staggered relation upon said holder to straighten the bristles of the brush, said lobed sections serving also to transfer blacking from the pick-up device to the brush.

4. In a blacking machine, a brush for applying blacking to heel peripheral surfaces, a blacking receptacle, a pick-up device for taking blacking from the receptacle, and a rotary transfer device interposed between the pick-up device and the brush constructed and arranged to straighten the bristles of the brush and provided with peripheral surfaces adapted to be brought into close relation to the pick-up device to receive blacking therefrom and transfer it to the brush.

5. In a blacking machine, a brush for applying blacking to heel peripheral surfaces, a blacking receptacle, a pick-up device for taking blacking from the receptacle, a rotary transfer device interposed between the pick-up device and the brush constructed and arranged to straighten the bristles of the brush and provided with peripheral surfaces adapted to be brought into close relation to the pick-up device to receive blacking therefrom and transfer it to the brush, and an adjustable eccentric bearing for said rotary transfer device constructed and arranged to permit adjustment of the transfer means toward and away from the axis of the pickup device to control the quantity of blacking transferred.

6. In a blacking machine, an applying brush, a supply receptacle and means for delivering blacking from the receptacle to the brush, comprising a rotatable drum and a comb member having substantially circular portions adapted closely to approach the surface of the drum to remove blacking therefrom and deliver it to the applying brush.

7. In a blacking machine, an applying brush, a supply receptacle, a rotatable pick-up device having a cylindrical portion dipping in and arranged to lift blacking from the receptacle, and transfer means for removing blacking from said cylindrical portion and delivering it to the applying brush, said transfer means comprising a plurality of sections constructed and arranged to approach closely to said cylindrical portion of the pick-up device to take blacking therefrom and arranged in staggered relation to exert a straightening action on the bristles of the brush.

8. In a blacking machine, an applying member, a supply receptacle, pick-up means for lifting blacking from said receptacle,

means for transferring the blacking from said latter means to the applying member, and means for supporting said transfer means, constructed and arranged to permit adjustment of the transfer means toward and away from the axis of the pick-up means.

9. In a blacking machine, an applying member, a supply receptacle, pick-up means for lifting blacking from said receptacle, and rotary means for transferring the blacking from said pick-up means to the applying member comprising a plurality of thin plates disposed substantially normal to the axis of rotation of the rotary means and provided with circular edge portions adapted to be brought into close proximity to the pick-up means to receive blacking therefrom for transfer to the applying member.

10. In a blacking machine, an applying member, a supply receptacle, a rotatable cylindrical pick-up device dipping in said receptacle for lifting blacking therefrom, and means for transferring the blacking from said cylinder to the applying member comprising a rotatable transfer device provided with a plurality of segmental blades disposed substantially normal to the axis of rotation of the transfer device and provided with curved edges arranged to move in close proximity to the surface of the cylindrical pick-up device to remove blacking therefrom for transfer to the applying member.

11. In a blacking machine, an applying member, a supply receptacle, a rotary cylinder dipping in the blacking in said receptacle, a rotatable transfer means having circular peripheral portions for transferring the blacking from the cylinder to the applying means, an eccentric bearing for said transfer means, and means for adjusting the position of said bearing to vary the approach of the transfer means to the pick-up cylinder.

12. In a blacking machine, an applying brush, a supply receptacle, a pick-up cylinder dipping in said receptacle, and a rotary transfer device interposed between the pick-up device and the brush comprising members having substantially circular portions adapted closely to approach the surface of the cylinder to remove blacking therefrom and deliver it to the applying brush, said members being also constructed and arranged to exert a clawing action on the bristles of the brush to straighten the bristles.

13. In a blacking machine an applying brush, a supply receptacle, a pick-up cylinder dipping in said receptacle, a rotary transfer device interposed between the pick-up device and the brush comprising members having substantially circular portions adapted closely to approach the surface of the cylinder to remove blacking therefrom and deliver it to the applying brush, said members being also constructed and arranged to exert a clawing action on the bristles of the brush to straight-

en the bristles, and means for adjusting the axis of rotation of said transfer means to vary the distance between the circular portions of said members and the pick-up cylinder.

14. In a blacking machine, an applying brush, a supply receptacle, a pick-up cylinder dipping in said receptacle, a rotary transfer device interposed between the pick-up device and the brush comprising members having substantially circular portions adapted closely to approach the surface of the cylinder to remove blacking therefrom and deliver it to the applying brush, said members being also constructed and arranged to exert a clawing action on the bristles of the brush to straighten the bristles, and means for varying the approach of the transfer means to the brush without disturbing the relation of the transfer device to the cylinder.

15. In a blacking machine, an applying brush, a supply receptacle, a pick-up cylinder dipping in said receptacle, a rotary transfer device interposed between the pick-up device and the brush comprising members having substantially circular portions adapted closely to approach the surface of the cylinder to remove the blacking therefrom and deliver it to the applying brush, said members being also constructed and arranged to exert a clawing action on the bristles of the brush to straighten the bristles, means for adjusting the relation of said transfer means to the cylinder, and means for varying the approach of the transfer means to the brush without disturbing the relation of the transfer device to the cylinder.

16. In a blacking machine, a rotatable comb for straightening the bristles of a blacking applying brush, said comb comprising a holder shaft and a plurality of thin plates having single projections and arranged side by side along said shaft in more than two positions which are angularly related to one another.

17. In a blacking machine, a rotatable comb for straightening the bristles of a blacking applying brush, said comb comprising a holder shaft and a plurality of thin sheet metal plates having sharp projections, said plates being arranged in contact with one another side by side along said shaft with successive plates angularly related to one another, and means for clamping said plates together in position upon the shaft.

18. In a blacking machine, an applying brush, a supply cylinder, and a rotatable comb for straightening the bristles of a blacking applying brush and transferring blacking thereto, said comb comprising a holder shaft and a plurality of plate sections mounted on the shaft, each of said sections comprising a hub portion and a projecting portion and said projecting portion having a circular end edge

- concentric with the axis of the shaft adapted to coact with said cylinder.
19. In a blacking machine an applying brush, a supplying cylinder, and a rotatable comb for straightening the bristles of a blacking applying brush and transferring blacking thereto, said comb comprising a holder shaft and a plurality of plate sections mounted on the shaft, each of said sections comprising a hub portion and a projecting portion and said projecting portion having a circular end edge concentric with the axis of the shaft adapted to coact with said cylinder and a straight edge intersecting the circular edge to form a sharp corner at the advancing side thereof, said straight edge being disposed along a line back of a radius joining said corner to the center of the shaft, whereby the corner may more effectively claw the bristles of the brush.
20. In a blacking machine, a blacking applying brush, a rotatable comb for straightening the bristles of said brush, a supporting and driving shaft for said comb having a shoulder, said comb comprising a holder threaded on said shaft and adapted to be brought up against said shoulder, and means for securing said comb to said holder.
21. In a blacking machine, an applying brush, a rotatable comb for straightening the bristles of said brush, said comb comprising a holder sleeve, a plurality of comb members mounted side by side on said sleeve, and means for clamping said members to said sleeve to permit adjustment of the comb in a direction parallel to the axis of the brush comprising clamping collars threaded to the sleeve and arranged to contact with each end of the comb assembly.
22. In a blacking machine, a rotary comb for straightening the bristles of a blacking applying brush comprising a holder having a longitudinal key and a plurality of identical plate sections arranged side by side upon the holder, each plate section comprising a hub portion having a plurality of key-ways so that it may be mounted in any one of several positions upon the holder and a projecting portion, said projecting portion being shaped to form a sharp corner at its advancing side to enter the bristles of the brush.
23. In a blacking machine, a rotary comb for straightening the bristles of a blacking applying brush comprising a holder having a longitudinal key, and a plurality of plate sections mounted side by side upon the holder and having lobed portions and hub portions, the hub portions being provided with a plurality of key-ways whereby said sections may be mounted in any one of several positions upon the holder to provide a comb with a corresponding number of projections.
24. In a blacking machine, an applying member, a blacking supply receptacle, means for transferring blacking from said receptacle to said member including a hollow drum having one side substantially closed by a flange which prevents the introduction of blacking to the interior of the drum as the latter dips into the receptacle.
25. In a blacking machine, blacking applying means, a blacking supply receptacle, a hollow member for taking blacking from the receptacle, and a transfer device for receiving blacking from said hollow member and delivering it to the applying means, said hollow member being constructed and arranged to prevent the accumulation of blacking in its interior.
26. In a blacking machine, an applying member, a supply receptacle, means for transferring blacking from said receptacle to said member including cylindrical means, said cylindrical means having an end surface, and means for scraping the blacking from said end surface comprising a member having a flattened face and mounted to turn about an axis alongside said surface to bring a corner of said face into co-operative relation with the said end surface.
27. In a blacking machine, an applying member, a supply receptacle, means for transferring blacking from said receptacle to said member including a surface normal to the shaft, means for scraping the blacking from said surface comprising a member having a sharp corner extending lengthwise of the member substantially parallel to its axis, and means for supporting said member with its axis disposed substantially parallel to said surface constructed and arranged to allow adjustment of said member about its axis to bring said corner into cooperative relation with said surface.
28. In a blacking machine, an applying member, a supply receptacle, means for transferring blacking from said receptacle to said applying member comprising a cylindrical member having parallel laterally displaced surfaces, and means for scraping blacking from said parallel surfaces comprising a pair of members one of which is adjustable to compensate for uneven wear of the two members of the pair.
29. In a blacking machine, an applying member, a supply receptacle, means for transferring blacking from said receptacle to said applying member including a cylindrical member, said cylindrical member having an outwardly projecting flange, and relatively adjustable scrapers constructed and arranged to control the blacking upon one face of said flange and an end face of the cylindrical member.
30. In a blacking machine, a blacking applying member, a supply receptacle, means for transferring blacking from said receptacle to said applying member comprising a member having a face one portion of which supplies blacking to said applying member,

- and scraper means comprising a readily adjustable part operating to control the blacking supplied by said portion of said face and a stripper adapted to clean said face adjacent to the portion thereof which supplies blacking to the applying member.
31. In a blacking machine, a blacking applying disk, a supply receptacle, means for transferring blacking from said receptacle to the applying member comprising a member having a circular face substantially normal to the axis of rotation of said member and overlapping said disk, an adjustable scraper constructed and arranged to control the quantity of blacking upon the annular margin of said circular face, and stripper means overlapping said scraper means for cleaning a portion of said face within said annular margin.
32. In a blacking machine, an applying member, a supply receptacle, a cylinder for transferring blacking from said receptacle to said applying member having a projecting flange, scrapers for the periphery of the cylinder, the side of the flange, and the end surface of the cylinder, a holder for said scrapers, means for adjusting said holder constructed and arranged to adjust the position of one scraper without disturbing the effective relation of the other scrapers to the cylinder, and means for relatively adjusting the scrapers for the flange and the end surface to compensate for uneven wear.
33. In a blacking machine, an applying member, a supply receptacle, a cylinder for transferring blacking from said receptacle to said applying member having a projecting flange, a scraper for controlling the quantity of blacking upon a plurality of adjacent surfaces of said cylinder comprising a block, the end surface of which is resiliently pressed against said flange, an elongated pin-like member rotatably mounted in said block at an angle thereto, said pin-like member having a sharp corner extending alongside the end surface of the cylinder and adapted to be brought into cooperative relation thereto by turning the pin about its axis and said block having a sharp-edged portion adapted to be brought into cooperative relation to the curved periphery of the cylinder to control the amount of blacking carried by said periphery, and means for rotating said scraper assembly about an axis substantially parallel to the axis of the cylinder, thereby to vary the quantity of blacking carried by the periphery of the cylinder without disturbing the relation of the scrapers coacting with the surface of the flange and the end surface of the cylinder to said surfaces respectively.
34. In a blacking machine, a frame, an applying member, a supply receptacle, a cylindrical means for transferring blacking from said applying member, an adjustable scraper

for controlling the quantity of blacking transferred by said cylindrical means, and means for supporting said adjustable scraper comprising a block detachably secured to the frame of the machine, said block being constructed and arranged for removal to remove the scraper and for replacement on the machine in its original position, thereby to maintain the adjustment of the scraper.

35. In a heel blacking machine, a rand crease blacking disk, means for supplying blacking to said disk arranged to contact with a lateral face thereof, means for cleaning the opposite lateral face of the disk, and means for adjustably supporting said disk and said cleaning means constructed and arranged so that the disk may be adjusted axially toward and away from the supplying means without disturbing the adjustment of the cleaning means with respect to the disk.

36. In a blacking machine, a disk having a lateral face for applying blacking to the surface of a shoe heel base in the rand crease, means contacting with said face of the disk for supplying blacking thereto, a plow arranged to contact with said face of the disk and operating to divert blacking toward the periphery of the disk, cleaning means contacting with the opposite lateral face of said disk, and an adjustable holder for supporting said disk, said plow and said cleaning means constructed and arranged to permit axial adjustment of the disk with respect to the supply means without disturbing the relation of the plow and cleaning means to the disk.

37. In a blacking machine, a disk having a lateral face for applying blacking to the surface of a shoe heel base in the rand crease, means contacting with said face of the disk for supplying blacking thereto, a plow arranged to contact with said face of the disk and operating to carry blacking received by the disk outwardly toward its periphery, and an adjustable holder for supporting said disk and said plow constructed and arranged to permit adjustment of the disk axially toward and from the supply means without disturbing the relation of the plow to the disk.

38. In a shoe blacking machine, a sectional applying member, driving means therefor, a removably mounted stud secured to the machine, a rotatable supporting sleeve on said stud and having an end abutment detachably connected to said driving means, means for securing one or more sections of said applying members upon said supporting sleeve in engagement with said abutment comprising an interrupted thread on said sleeve and a quickly removable co-acting nut having an interrupted thread, the end surfaces of said nut being differently related to its thread so that it may be reversed to insure a tight clamping engagement.

39. In a machine for blacking shoes, a rotatable support provided with an abutment flange and hub-like extension, a brush placed over said extension in engagement with said abutment flange whereby the spread of the bristles at one side is limited, an interrupted thread on said extension, a co-acting nut provided with an interrupted thread, an external projection on said nut, whereby said nut may be slid into engagement with the end of the brush and tightened against the brush by engaging said projection to give it a partial rotation, and a separate disk rotatably supported for engagement with the other side of the brush, said disk having a slot for engagement with the projection on said nut whereby said disk may be rotated with the brush irrespective of whether or not the brush and the disk are concentric.
40. In a blacking machine, a removable fluid receptacle, an agitator in said receptacle movably attached to the receptacle and removable from the machine with the receptacle, and driving means upon the machine and constructed and arranged intermittently to engage the agitator to vary the position of the agitator with respect to the receptacle without interfering with removal of either from the machine.
41. In a blacking machine, a removable blacking receptacle, an agitator in said receptacle pivotally attached to the receptacle for removal therewith, and driving means upon the machine constructed and arranged detachably to engage the agitator to move it with respect to the receptacle, thereby allowing removal of the receptacle without disturbing the pivotal connection of the agitator to the receptacle.
42. In a blacking machine, an applying device, a rotary member dipping in the receptacle to raise blacking for delivery to the applying device, an agitator arranged along side said rotary member and pivotally attached to the rim of the receptacle, and driving means upon the machine constructed and arranged for intermittent engagement with said agitator to vary its position with respect to the receptacle.
43. In a blacking machine, a driven shaft, a blacking receptacle, an agitator arm pivotally mounted on said receptacle for up and down movement therein and provided with an overhanging cam-shaped flange, and a cam roll upon said shaft and arranged for intermittent engagement beneath said flange to raise the agitator arm and allow it to drop back into the receptacle.

In testimony whereof I have signed my name to this specification.

HERBERT L. CHAPIN.
